UNITED STATES PATENT OFFICE

WILLIAM C. ROBERTSON, OF DORCHESTER, MASSACHUSETTS

WATCH WINDER

Application filed March 12, 1929. Serial No. 346,483.

The present invention relates to novel watch winders and stem pullers, particularly adapted for use in connection with ladies' watches and wrist watches, although not limited thereto.

In wrist watches, and particularly ladies' wrist watches, which are of small size, it is a difficult, as well as a delicate operation, to wind the same, due to the smallness of the crown, the fineness of the knurling thereon, and the strength of the main spring of such watches, due to the reduced size thereof. When winding by hand, it frequently occurs that the winder will exert too much strength and snap the main spring. As the tension on the spring increases, also, the fingers of the winder may be hurt by the knurled crown.

Furthermore, in watches of this type, the crown, which is of course attached to the main spring winding stem, is set so close to the body of the watch as to render it difficult to pull said crown and stem for the purpose of setting the hands of the watch. Broken finger-nails are only one of the many difficulties associated with this particular operation.

An important object of the present invention, therefore, is the provision of a device which will combine the properties of a winder and a stem puller, being provided with separate means for accomplishing each of these operations.

Another object of the invention is to provide such a device that will wind a watch to a desired degree, but which will render it substantially impossible to break the main spring during use thereof.

Another object of the invention resides in the provision of means, preferably remote from the winding device, to engage the crown of the watch and separate it from the watch case a sufficient distance to permit setting of the hands of said watch.

In carrying out my novel idea, I utilize as the winding medium of my novel device a friction member, preferably rubber, although other friction material may be utilized if desired. This material will exert sufficient friction on the crown of the watch to wind the main spring thereof to the desired point,

but when such point has been reached, the friction material will slip over said crown, thus apprising the operator that the watch is completely wound.

In order to effect the stem pulling operation, I provide my novel device with a substantially V-shaped notch, preferably at the end remote from the friction clutch member, and preferably bevel each side of the device adjacent to the said notch. This permits the notched end of the device to be slid between the crown and the case, and over the stem. The bevel or wedge shape of the notched end will exert a preliminary pressure on the crown of the watch, tending to force the same away from the case of the watch. Since my novel device is of relatively thin material, it will have a degree of flexibility or "spring". This "spring" of the material will assist in forcing the crown away from the case, permitting the stem to be rotated by said crown to set the hands of the watch.

My novel device may be made of metal, celluloid, single or multi-ply composition, and may be made in any desirable color or combination of colors. It is inexpensive and simple to manufacture, is simple to operate, and the advantages of the same will be readily understood and appreciated by those skilled in the art, as well as by the users thereof.

I believe that the combined watch winder and stem puller above described is novel, and I have therefore claimed the same broadly in the present application.

The above and other features of the invention, details of construction and advantages, will be hereinafter more fully pointed out, described and claimed.

Referring to the drawings, illustrating a preferred embodiment of the invention,

Fig. 1 is a perspective view of my novel device from the top thereof;

Fig. 2 is a perspective view of said device from the bottom thereof; and

Fig. 3 is a longitudinal sectional view on the line 3-3 of Fig. 2, illustrating the device in position for winding a watch.

Referring now to the drawings for a particular description of the invention, 1 design-

nates the body of my novel device. This body 1 may be formed of any desirable material, such as metal, single or multi-ply celluloid, single or multi-ply composition, ivory, or any 5 material capable of such use, and may be produced in any desirable color or combinations of color. If formed of multi-ply material, the upper layer may be of one color and the lower layer of a contrasting color, thus producing a pleasing and attractive ornamental 10 effect.

At one end of this body portion 1 the material is bent or molded, as illustrated at 2, to form a substantially U-shaped groove or 15 trough 3, within which is applied or affixed a piece or mass 4 of friction material, preferably rubber as illustrated, although leather, cork or other suitable friction material may be utilized. The free edge of the body out- 20 side of the material 4 is beveled, as at 5, to a relatively thin edge. Thus, when the device is applied to a watch 9, as illustrated in Fig. 3, in which the crown 8 is close to the watch, the beveled edge 5 will permit the friction 25 material or clutch 4 to engage the crown 8 and upon movement thereover, to effect a winding thereof and of the main spring.

The body 1 tapers from the clutch end, as clearly illustrated, and terminates in a sub- 30 stantially V-shaped notch 6, the sides of the body 1 adjacent to said notch being beveled, as illustrated at 7. This permits the notched end of the device to be inserted between the crown 8 and case 9, over the stem of the watch, 35 and the tapered portions 7 will effect a wedging action on the crown 8, tending to force said crown away from the watch 9. If the wedging action per se should not be sufficient, the operator can tilt the device, and thus ef- 40 fect a more forcible separation of the crown from the watch, pulling the stem out a sufficient distance to permit setting of the hands of the watch. Since the material of which the device is formed, due to its thinness, will 45 have an inherent flexibility, such flexibility will still further assist in separating the crown from the case. The advantages of this feature will be instantly apparent, eliminating broken finger-nails and other difficulties and troubles incident to pulling the stem to set the hands.

When winding a watch, it is only necessary for the operator to take the device in one hand, and if the watch is on the wrist for, 55 example, to simply apply the clutch member 4 to the crown of the watch, and rub the same back and forth over the crown. This rubbing, and the friction of the clutch 4 on the knurled crown 8, will effect a winding of the 60 main spring of the watch. When the main spring has arrived at the proper tension, such tension will be sufficient to overcome the friction of the clutch 4, and will cause said clutch to slide over the crown without any 65 harmful effect on the watch or main spring.

It will thus be appreciated and understood that I have devised a simple, economical, and efficient device of this character, and one which I believe is entirely novel.

It will be appreciated that I may vary the 70 size, shape and arrangement of the device within reasonably wide limits without departing from the spirit of the invention.

My invention is further described and defined in the form of claims as follows:

1. A device of the kind described, comprising a body portion having a groove therein adjacent to one end thereof, and a friction member in said groove, the edge of said body portion adjacent to the outer edge of said friction member being beveled to a relatively 80 thin edge.

2. A manually operable watch winder, comprising a plate having a substantially U-shaped elongated groove therein adjacent to one edge thereof, and an elongated friction member in said groove adapted to engage the knurled crown of a watch, whereby a back and forth movement of said winder while 85 said friction member is in engagement with said crown, will effect a winding of said watch.

In testimony whereof, I have signed my name to this specification.

WILLIAM C. ROBERTSON.
